ELECTRIC LIGHT FIXTURE

Louis D. Phillips, 32-02 Queens Blvd.,
Long Island City, N.Y.

Filed Sept. 14, 1959, Ser. No. 57,542

Term of patent 3½ years

(Cl. D48—23)

FIG. 1.

FIG. 2.

FIG. 1 is a bottom plan view of an electric light fixture embodying my new design;

FIG. 2 is a side elevational view thereof.

The sides of the electric light fixture not shown are the same in appearance as the side shown and the top is substantially plain.

I claim:

The ornamental design for an electric light fixture, substantially as shown and described.
